UNITED STATES PATENT OFFICE

113,703

DESIGN FOR A REFLECTOR LENS OR THE LIKE

Clark M. Bolser, Cedar Falls, Iowa, assignor to
The Bolser Corporation, Cedar Falls, Iowa, a
corporation of Iowa

Application August 23, 1937, Serial No. 71,293

Term of patent 3½ years

To all whom it may concern:

Be it known that I, Clark M. Bolser, a citizen
of the United States and a resident of Cedar Falls,
in the county of Blackhawk and State of Iowa,
have invented a new, original, and ornamental
Design for Reflector Lens or the like, of which
the following is a specification, reference being
had to the accompanying drawing, forming part
thereof.

Figure 1 is a front elevational view of a re-
flector lens or the like showing my new design.

Figure 2 is an edge elevational view thereof.

Figure 3 is a rear elevational view thereof;
and

Figure 4 is a sectional view on the line 4—4
of Figure 3.

The design is characterized by a dome-shaped
lens of the contour shown, having the interior
thereof provided with prisms of the specific con-
figurations and arrangements shown.

I claim:

The ornamental design for a reflector lens or
the like, substantially as shown and described.

CLARK M. BOLSER.
